(57) **CLAIM**

The ornamental design for a combined spray bottle and cap, as shown and described.

DESCRIPTION

FIG. 1 is a front view of a combined spray bottle and cap showing our new design, the rear view being symmetrical to the front view;

FIG. 2 is a left side view thereof;

FIG. 3 is a right side view thereof;

FIG. 4 is a top plan view thereof;

FIG. 5 is a bottom plan view thereof, showing a shallow concavity that is recessed approximately $\frac{1}{100}$ of the overall height of the combined spray bottle and cap; and,

FIG. 6 is a perspective view thereof.
